Primary Examiner — Mary Ann Calabrese*Assistant Examiner* — Catherine Ho(74) *Attorney, Agent, or Firm* — Peter L. Brewer; Thrive IP(57) **CLAIM**

The ornamental design for an IT server tag, as shown and described.

DESCRIPTION

FIG. 1 is a top right perspective view of an IT server tag, showing my new design in an open position.

FIG. 2 is a bottom left perspective view thereof.

FIG. 3 is a front elevation view thereof.

FIG. 4 is a rear elevation view thereof.

FIG. 5 is a top plan view thereof.

FIG. 6 is a bottom view thereof.

FIG. 7 is a right side elevation view thereof.

FIG. 8 is a left side elevation view thereof.

FIG. 9 is a right side elevation view of an IT server tag shown in a folded position; and,

FIG. 10 is a left side elevation view thereof.
